UNITED STATES PATENT OFFICE.

VICTOR WILLOUGHBY, OF JEFFERSONVILLE, INDIANA, ASSIGNOR TO AMERICAN CAR AND FOUNDRY COMPANY, OF ST. LOUIS, MISSOURI, A CORPORATION OF NEW JERSEY.

MAIL-POUCH RACK WITH EXPANSIBLE GRIP.

1,170,593.

Specification of Letters Patent.

Patented Feb. 8, 1916.

Application filed September 2, 1914. Serial No. 859,886.

To all whom it may concern:

Be it known that I, VICTOR WILLOUGHBY, residing at Jeffersonville, Clark county, Indiana, and being a citizen of the United States, have invented certain new and useful Improvements in Mail-Pouch Racks with Expansible Grips, of which the following is a full, clear, and exact description, such as will enable others skilled in the art 10 to which it appertains to make and to use the same, reference being had to the accompanying drawings, which illustrate the preferred form of the invention, though it is to be understood that the invention is not limited to 15 the exact details of construction shown and described, as it is obvious that various modifications thereof will occur to persons skilled in the art.

In said drawings: Figure 1 is a plan view 20 of the improved mail pouch rack, different positions of members forming parts of the expansible grips being shown in dot and dash lines. Fig. 2 is a side elevation of the device, intermediate and end portions, respectively, of the standards and a pair of section-connecting crosses being broken away. Fig. 3 is a front elevation of said rack. Fig. 4 is an enlarged fragmentary perspective view of one section of the rack, 30 a pouch being shown as held in place by one of the unit racks. Fig. 5 is a transverse view of one of the rack sections, partly shown in section, and further discloses the manner of supporting a pouch. Fig. 6 is an enlarged fragmentary plan view, illustrating the preferred means for connecting certain elements of the rack, including one of the standards. Fig. 7 is a side elevation of the parts shown in Fig. 6. Fig. 8 is a transverse view thereof, partly in section; and, 40 Fig. 9 is a side elevation of a modified and preferred form of means for connecting those rack sections which are not secured to the standards.

Except for highly developed organization and perfected equipment, modern postal systems would be reduced to a chaotic state, quite incapable of handling the vast quantities of mail matter presented to traverse 50 their arteries and ramifications.

With a view to contributing to the efficiency of such systems, the present invention has been developed, and pertains to mail

pouch racks designed to occupy a minimum amount of space and to permit the utilization of substantially all of it.

An aim is to provide a multiple rack comprising grouped unit racks connected to a frame to have a common non-interfering support, each unit rack being independent 60 of the others and arranged to be used with equal facility.

Another object is to provide each unit rack with an expansible grip adapted to be adjusted to the mouth or opening of any of 65 a number of different sized pouches, which grip may be quickly and expeditiously rendered effective, or likewise releasable, when the pouch has received its allotted contents.

An important advantage lies in being able 70 to construct the rack nearly or entirely from commercial products, purchasable in the open market, and adapted to be assembled with very little preliminary shop treatment, the parts being interchangeable and easily 75 repaired or substituted.

Referring to the drawings, 1 indicates a forward standard and 2 a rear standard, the latter being taller than the former, and both preferably being ordinary tubes or 80 pipes. Bases for said standards each comprises a four-way T fitting 3, screwed or otherwise secured to the lower end of its respective standard, 1 or 2, oppositely directed transversely disposed tubes or pipe 85 lengths 4, threaded onto the outer ends of which are elbows 5, plugs 6, if desired, being inserted into the downwardly extending portions of said elbows.

Where conditions make it desirable, 90 threaded nipples may replace plugs 6 and be screwed into floor plates, the rack being thus anchored to the floor. On the other hand, casters may be substituted for plugs 6, allowing the rack to be easily moved to 95 any desired location. But the use of plugs 6 is most approved, as a rack supplied with them will better remain where placed than when casters are used, but may be changed in location at will.

Bases of standards 1 and 2 are connected by the tie member 11, shown as a tube which is screwed into the four-way T's 3 of each standard base, and the upper portions of standards 1 and 2 are bent or inclined and 105 have secured to upper extremities fittings

which may be the pipe T's 7, but preferably are the cast connection fittings, one of which is shown in Figs. 6 to 8 inclusive.

In the form illustrated in Figs. 1 to 5, 5 pipe T's 7 connect the top frame or multiple rack 8 to the standards 1 and 2, said multiple rack comprising a series of twin sections 9 of unit racks 10. Extending along the longitudinal median line of multiple rack 8 10 is a supporting or "backbone" member common to the multiple rack 8 and all of unit racks 10, and forming the inner side of each of the latter. Said central or "backbone" member comprises end fittings, as T's 12, in alinement with the outer sides of the 15 end unit racks 9, crosses 13, alined with the inner sides of said end unit racks and with both sides of the intermediate racks 9, the T's 7 which connect the multiple rack 8 to 20 standards 1 and 2 and tubes or pipes 14 and nipples 15 which connect the crosses or fittings together. One nipple 15 is shown in Fig. 2, where a pair of adjacent crosses 13 have been broken away to disclose it.

25 Screwed into or otherwise secured to end T's 12 and to intermediate crosses 13 the tubes 16, provided at their outer ends with removable caps 17, each of which may be threaded onto one of the transverse tubes. 30 Telescopically mounted within pairs of transverse tubes 16 are the side arms of a substantially U-shaped pouch-engaging tube or bar 18.

In assembling, caps 17 are slipped onto 35 the side arms of slidible tube or bar 18, and the free ends of said arms are upset to prevent the withdrawal of caps 17. Side arms of tube or bar 18 are then inserted into the transverse tubes 16, whereupon caps 17 are 40 screwed onto the ends of said transverse tubes.

As shown in Fig. 5, the side arms of tube or bar 18 are notched, as at 19, the spacing of the notches being such as to cause the 45 expandible grip for the notches to be regulated in accordance with standard dimensions of the pouch openings. The upset free ends of sliding tubes or members 18 cannot pass through caps 17, now fixed to 50 the ends of transverse tubes 16, but each member 18 may be slid to any one of its notched positions, and the notches on the side arms will be caused by gravity to engage with the edges of the apertures through 55 which said arms pass, retaining said tube or member in the position to which it is pulled. To return said sliding tube or member 18 to its original or any other of its accentuated positions, it is simply raised sufficiently to disengage it from caps 17, when 60 it may be moved inwardly or outwardly within the limits of its possible travel.

At any convenient points, but preferably to the undersides of the end T's 12 and 65 crosses 13 of the central supporting member

or "backbone," are secured double holding clips 20, adapted to coöperate with the outer and intermediate portions of tubes or members 18 to support pouches. Said outer portions, which parallel the central supporting member, are brought into substantially the same horizontal plane as the pouch supporting prongs of clips 20 by the downward and outward bending of the side arms of said members 18.

75 The top frame or multiple rack 8 is inclined upwardly as it proceeds rearwardly, so that label holders may be secured to each unit rack 10, and clearly discerned from the front of the complete rack structure. Obviously, the rack may be caused to incline in other directions when it is preferable for it to do so.

80 As stated hereinbefore, crosses 13 and the T's 7 which connect the standard and multiple rack do not constitute the preferred forms of connecting means in the central supporting member of said multiple rack. For joining the multiple rack 8 to standards 1 and 2, I prefer to employ castings like that shown at 21 in Figs. 6 to 8 85 inclusive.

90 Said casting is the equivalent of a pair of crosses and a T fitting, and occupies less space than the corresponding fittings shown 95 in Figs. 1 to 5, makes a firmer and more reliable joint and connects pipes 14 of the central supporting member, transverse tubes 16 and standard 1 or 2 in practically the same manner they were connected in the 100 form shown in Figs. 1 to 5.

Aside from the improved qualities mentioned, the chief difference between the standard fittings 7 and 13 and the casting 105 21 is the locating of the standard between adjacent racks, which is a more desirable position than it occupies in the first described form. Castings 21 are also formed to have improved clip-attaching surfaces on the under faces of bosses 22.

110 Casting 23, shown in Fig. 9, is the equivalent of a pair of crosses such as are shown in Figs. 1 to 4, and is adapted to connect those adjacent rack sections which are not connected to either standard 1 or 2. Said casting 23 constitutes the preferred connection means for such sections, and has the same advantages as casting 21, except with regard to the positioning of the standards, it having no association with the latter. 115 The tubular members 1, 2, 14 and 16, in addition to being screwed into castings 21 or 23 are held from disconnection therewith by rivets 24, shown in Figs. 6 to 9, but equally applicable to the fittings of the structure 120 shown in 1 to 5.

125 In employing my improved rack, as many unit racks 10 are utilized as there are pouches to be suspended for filling, up to the capacity of the multiple rack 8. It be- 130

ing required to fill a pouch A, its draw string B is loosened and its mouth opened, a portion of the edge of the material defining the mouth or opening being slipped over the hook ends of clips 20 associated with the unit rack from which the pouch is to be suspended. The U-shaped pouch-engaging members 18 being fully telescoped within the transverse tubes 16 of said unit rack, that portion of the edge of the pouch opening opposite the portion between the engaging clips 20 is drawn over the depressed portion of said slideable pouch-engaging member 18, and said member is pulled outwardly to the capacity of the mouth of the pouch A. Upon reaching the limit of said mouth, the predeterminedly spaced notches 19 in the side arms of members 18 engage the caps 15, as previously set forth, and the pouch is firmly held in place, the material thereof surrounding said mouth lapping the hook ends of clips 20 and the outer edge of member 18. After the pouch receives its assigned contents, member 18 is slightly raised and pushed inwardly, and the pouch is released from said unit rack, and the draw-string B is pulled to close the pouch opening, after which the string is fastened or tied. In Fig. 1, different positions of the member 18 are shown, such variance allowing each unit rack to accommodate pouches of different capacities with their consequent various sized openings or mouths.

It is manifest that I have devised a mail pouch rack, having a light skeleton frame, which may be composed either of tubes or piping of commercial character, connected preferably by the special castings described, or by ordinary pipe or tube fittings, or the equivalents of either. It is also clear that many of the parts may be constructed of structural shapes instead of tubes.

The operation is simple, consumes a negligible amount of time and there is little opportunity for the parts to become broken or deranged. The rack is not costly, and may be made in various sizes from a single unit rack, or a single twin section, to a multiple rack of any desired dimensions, and each unit rack is adapted to accommodate pouches of varying sizes.

What I claim is:—

1. In a device of the class described, a supporting frame, and a multiple rack secured thereto and comprising a series of connected unit racks, each of the latter being provided with expansible pouch-gripping means adapted to hold the pouch with its opening distended.

2. In a device of the class described, a supporting frame, a multiple rack carried thereby and comprising a series of unit racks, said multiple rack having a central supporting member attached to said frame and forming one side of each unit rack, and

expansible pouch-gripping means in each of the latter adapted to hold the pouch with its opening distended.

3. In a device of the class described, a supporting frame, a multiple rack carried thereby and comprising a central supporting member and a series of connected rack sections each containing oppositely extending unit racks, said central supporting member forming part of each of said unit racks, and expansible pouch-gripping means in each of the latter adapted to hold a pouch with its opening distended.

4. In a device of the class described, a supporting frame, an inclined multiple rack carried thereby and comprising a central supporting member and a series of connected twin sections of unit racks symmetrically disposed each side of said central member, and expansible pouch-gripping means in each unit rack adapted to hold the pouch with its opening distended.

5. In a device of the class described, a supporting frame, a multiple rack carried thereby and comprising a common supporting member and a series of unit racks mounted thereon, and expansible pouch-gripping means for each unit rack comprising fixed holding members and a movable member forming part of said unit rack.

6. In a device of the class described, a multiple rack comprising sections of unit racks, a central supporting member in said multiple rack common to each unit rack and comprising a plurality of segments connected by fittings, the latter connecting said unit racks to said central supporting member, means secured to said central member for supporting said multiple rack, and expansible pouch-gripping means for each unit rack adapted to hold a pouch with its opening distended.

7. As an article of manufacture, a tubular supporting frame with laterally extending bases, a tubular multiple rack comprising a central supporting member constructed of segmental tubes and fittings connecting the same, a plurality of unit racks secured to said fittings and extending from opposite sides of said central member, and expansible pouch gripping means for each unit rack adapted to hold a pouch with its opening distended.

8. In a device of the class described, a supporting frame comprising tubular forward and rear standards, the latter exceeding the former in height, each standard being provided with a base comprising a four-way T-fitting, laterally and oppositely extending tubes attached thereto and elbows secured to said tubes, a tubular tie member connecting said four-way T-fittings and a multiple rack carried by said supporting frame and comprising a central supporting member, and a series of expansible pouch-

gripping racks disposed on opposite sides thereof.

9. As an article of manufacture, a tubular supporting frame with outwardly extending bases, and a multiple rack supported by said frame and comprising a central supporting member constructed of tubular segments and fittings having longitudinal and transverse extensions connecting said segments, some being located at the ends of said central member, oppositely extending transverse tubes secured to the transverse extensions of said fittings, slideable pouch-gripping members having spaced arms telescoped within pairs of said transverse tubes, caps on the ends of the latter preventing the withdrawal of said arms, and double pouch-engaging clips secured to said fittings.

10. In a device of the class described, a rack comprising a supporting member and a pair of transverse tubes projecting out-

wardly therefrom, a U-shaped slideable engaging member the side arms of which are predeterminedly and plurally notched, telescoped within said transverse tubes and upset at their free ends, caps with openings through which said arms slide secured to the outer ends of said transverse tubes and adapted to prevent the withdrawal of said U-shaped member and to cooperate with 25 said notches in the side arms thereof to position said U-shaped member, and pouch-holding clips secured to said supporting member, the closed end of said U-shaped member being positioned substantially in 30 the plane of said clips.

In witness whereof I have hereunto set my hand in the presence of two witnesses.

VICTOR WILLOUGHBY.
